UNITED STATES PATENT OFFICE.

KINGMAN NOTT CATHER, OF COLORADO SPRINGS, COLORADO.

LOCK.

No. 893,442.

Specification of Letters Patent.

Patented July 14, 1908.

Application filed January 16, 1908. Serial No. 411,103.

To all whom it may concern:

Be it known that I, KINGMAN NOTT CATHER, a citizen of the United States, and a resident of Colorado Springs, in the county 5 of El Paso and State of Colorado, have invented a new and Improved Lock, of which the following is a full, clear, and exact description.

My invention relates to locks, my more 10 particular purpose being to make an improved type of lock suitable for use upon cars and adapted to be sealed.

My invention embraces certain new internal parts of the lock and their relative arrangement, for the purpose of increasing the security afforded by the lock and also simplifying the construction.

My invention further relates to means whereby several locks upon the same car may 20 be secured by a single seal, by aid of a wire, string or other longitudinal flexible member.

Reference is to be had to the accompanying drawings forming a part of this specification, in which similar characters of reference indicate corresponding parts in all the figures.

Figure 1 is a front elevation of a lock as applied to a car door, the parts being in their normal positions and the door being locked. Fig. 2 is an enlarged central section upon the 30 line 2—2 of Fig. 1, looking in the direction of the arrow and showing the bolt extending through the staple, so as to secure the hasp, this view further showing the seal (having the form of a brittle plate) so disposed that 35 the latter must be broken before the bolt can be withdrawn from the staple; Fig. 3 is an enlarged elevation somewhat similar to Fig. 1, but showing the bolt as withdrawn from the staple; Fig. 4 is an enlarged horizontal 40 section upon the line 4—4 of Fig. 2, looking in the direction of the arrow and showing the bolt together with the slide and keeper for controlling the bolt; Fig. 5 is a fragmentary side elevation showing the construction 45 closed in Fig. 1 viewed as from the right of said figure, this view further showing the slot through which the brittle plate serving as a seal is inserted in order to prevent tampering with the bolt; Fig. 6 is an elevation showing 50 the back plate provided with the slideway containing the slide, this view also showing a keeper of semicircular form in the position which it occupies when the bolt is thrown so as to lock the door; Fig. 7 is a fragmentary 55 side elevation viewed as from the left of Fig. 1 and showing the slide provided at its top

with a heart-shaped pocket, and at its bottom with a rounded boss for the purpose of enabling the keeper to control the bolt; Fig. 8 is a side elevation somewhat similar to Fig. 60 7 but showing the slide as drawn toward the front by aid of a key, in order to release the bolt so as to permit it to be withdrawn; Fig. 9 is a section upon the line 9—9 of Fig. 6, looking in the direction of the arrow, and 65 showing the back plate provided with a straight slideway for the slide and with a curved slideway for the keeper, the slide and the keeper, however, being removed; Fig. 10 is a fragmentary rear elevation of the bolt 70 and slide; Fig. 11 is an enlarged plan view of the keeper; Fig. 12 is a perspective of the key used for operating the lock; and Fig. 13 is an elevation partly broken away, showing another form of my improved lock in which a 75 number of balls are substituted for the keeper, and in which certain portions are rendered compound or double-acting.

A casing 14 is provided at its lower end with a flat portion 15, and is further provided with lugs 16. Countersunk bolts 17 pass through these lugs, and countersunk bolts 18 pass through the flat portion 15, for the purpose of securing the casing upon a car. The casing 14 is also provided with a 80 projecting portion 19, having upon its front face a shelf 20 for the purpose of warding off rain or snow. A bolt 21 is slidably mounted within the casing and is preferably of about the same length as the latter, extending entirely through the projecting portion 19 of 85 the casing. The bolt 21 has, for the most part, the proximate form of a large flat bar and is provided at its upper end with a ring 22, whereby it may be raised when otherwise 90 freed. The bolt 21 is further provided with a facing 27^a, which is merely a flat surface slidably engaging the inner wall of the casing. This facing has the shape of a keystone 95 in order to allow the broken parts of the seal 100 to more readily drop out at the bottom. The bolt 21 is provided at its lower end with a cylindrical portion 23, and this portion is provided with holes 24, 25, of different sizes, extending directly through it. A staple is 105 shown at 26 and is mounted rigidly upon the lower portion 15 of the casing. The purpose of the hole 24, is to have strings or wires passed through a number of them in succession where several locks are used upon the 110 same car, in order that a single seal may suffice for all or any desired number of the locks,

by means of a wire, cord, tape or other flexible material, being strung through the holes 24, of bolts of several locks other than the lock that is to hold the seal; and the ends of the wire, cord or flexible tape to be held by the holes 25 of the lock that has the seal. Where the hasp cannot be readily fitted over the staple 26, a short piece of wire, cord or flexible tape can be fastened by threading 10 through the hasp and then threaded through the holes 25 in the member 23, and then sealed and locked. A hasp 27 is provided with a portion 28 and with a hinge 29, the portion 28 being secured upon a car door 28^a. 15 The hasp is slotted and is adapted to engage the staple 26 in such a manner as to hold the door securely closed when the parts are in the position indicated in Fig. 1, the bolt 21 being now in its lowermost position and being held 20 rigidly in such position, as hereinafter described.

The casing contains a large compartment 30 which contains most of the movable parts. A finger guide 31, having substantially a 25 crescent form, is integral with the portion 19 of the casing. The portion 19 is further provided immediately adjacent to the finger guide 31 with a slot 30^a for facilitating the entrance of the seal. A back plate 32, having generally the form indicated in Fig. 6, is provided with a longitudinal slot 32^a extending from one of its ends to the other, and is further provided with a portion 33 having a slot 33^a of substantially arcuate form. The 30 slot 33^a is separated from the slot 32^a by a wall 33^b having at its base a groove 33^c to give the boss 41 room in which to travel vertically, as hereinafter described.

Mounted within the slot 32^a and movable 40 in the general longitudinal direction thereof is a slide 34 having a projecting face 35. This face is provided with a key-hole 36 of substantially arcuate form. A key head 37, also of arcuate form, is adapted to partially enter 45 the key-hole 36. This key head is mounted upon a handle 38 provided with a weight 39, and has no connection with the lock except when applied to it for the purpose of controlling its movable parts, as will be understood 50 from Figs. 8 and 12. The slide 34 is provided with a bearing face 40 slightly curved and with a plane surface 42 bounding this bearing face, as indicated in Figs. 6 and 7, and is further provided with a boss 41 having 55 substantially the form of a spherical segment, this boss being rigid upon the slide 34 and preferably integral therewith (see Fig. 7). The slide 34 is also provided with a portion 42 bounding the bearing surface 40. Slid- 60 ably mounted within the slot 33^a is a keeper 43 having the form of a rod of general arcuate form and free to move longitudinally within certain limits permitted by the slot. The slide 34 is provided with a pocket 44, the lat- 65 ter being merely an indentation, substan-

tially heart-shaped, as will be understood from Fig. 7. A ball 45 is disposed within the upper end of the arcuate slot 33^a and is adapted to partially enter the pocket 44. The lower end of the keeper 43 is provided 70 with a reduced end 46 as will be understood from Fig. 11. This reduced end is rounded and is adapted to loosely engage the rounded stud 41. The upper end of the keeper is provided with a concave bearing 47 (see Figs. 6, 75 11) which engages the ball 45. The slide 34 is further provided with shoulders 48, 49, and these shoulders are engaged by shoulders 50, 51, respectively carried by the bolt 21 (see Figs. 7 and 8). The horizontal play of the 80 slide 34 relatively to the bolt 21, that is to say, the distance which it can be drawn forwardly by the key as indicated in Fig. 8, is limited in one direction by the mating of the shoulder 48 with the shoulder 50, and the 85 shoulder 49 mating the shoulder 51. The bolt 21 is provided upon its rear face with a semicircular aperture 52 merging into a slot 53. This is for the purpose of allowing freedom of movement of the lower end of the 90 keeper 43 where it comes into engagement with the rounded boss 41. As the slot 32^a in the back plate 32 registers with the slot 53 in the bolt 21, the slide 34, when drawn toward the front of the lock by the hand-operated key as above described, moves further into the slot 53. In doing this (see Fig. 4) the ball 45, being unable to follow the slide 34 because of the presence of a pin 55, is displaced slightly in a lateral direction and 95 presses upon the adjacent end 46 of the keeper 43. This causes the opposite end 46 of the keeper to move in behind the rounded boss 41 (see Fig. 6), and the result is that the slide 100 34 may be moved freely upward, or in other words, the device occupies the condition commonly designated as unlocked. If, now, the bolt be moved upward by hand, the keeper 43 drops downwardly into its lowermost position (see dotted lines in Fig. 3). 105 In order to allow the bolt 21 the proper freedom of movement, as above described, and yet to allow the pin 55 to retain the ball 45 in position, an aperture 56 is made in the slide 34, as will be understood from Fig. 4. 110 A seal 54 having the form of a rectangular brittle plate is employed for the purpose of securing the bolt when the door is locked. In order to insert the seal, it is taken into the hand and inserted into the slot 30^a while the 115 bolt 21 is raised, as indicated in Fig. 3. The bolt is now pushed downwardly so as to occupy the position shown in Fig. 2. The seal 54 now covers the face 35 of the slot 34 and consequently protects the key-hole 36. As the bolt and slide descend, the rounded boss 41 engages the rounded lower end 46 of the keeper 43 and thus displaces the keeper. The latter is forced slightly upward owing to the cam-like action of the rounded boss 41 120 125 130

upon the rounded end 46. The upward movement of the keeper 43 causes its upper bearing end 47 to force the ball 45 into the pocket 44, which is located upon the left edge 5 of the slide according to Figs. 1 and 3. It is obvious that the keeper 43 cannot move in either direction so long as the bolt occupies this position, and it is equally obvious that the bolt cannot be moved without first 10 placing the slide 34, and this cannot be done without breaking the seal. Now, to release the bolt, the operator breaks the seal, inserts the head 37 of the manually-operated key into the key-hole 36, pulls the head 34 toward the front and raises the bolt by hand, as above described. The seal when once in position within the lock and the bolt 21 is moved forward, the seal cannot be displaced, for the reason that it passes out of alignment 15 with the opening through which it is inserted (see Fig. 5).

Fig. 13 shows another form of my invention in which the mechanism is partly duplicated in order to allow the bolt to be secured 20 in either of its two extreme positions. By aid of this device the operator can leave the bolt in such condition that it is necessary to break the seal to either unlock or to lock the door. The casing is shown at 57 and the 25 sliding bolt at 58. A slot 59, of arcuate form, is filled with loose balls 60. A slide 61 (corresponding to the slide 34 in Fig. 6) is provided with a face 62 (corresponding with the face 35, Fig. 6) and is further provided 30 with a key-hole 63. The face 62 is adapted to register with an aperture 64 so that by aid of a key the slide can be drawn out substantially as above described with reference to the slide 34. The casing 57 is provided 35 with another aperture 65 analogous to the aperture 64, and with an opening 66 and a guard 67 to facilitate the admission of a seal. The slide 61 is provided with pockets 68, 69, and adjacent to these pockets and carried by 40 the bolt 58 are pins 70, 71. The action of the lock shown in Fig. 13 is substantially the same as that of the lock shown in the other figures, with the exception that two seals may be employed so that the bolt 58 is secured 45 in either of its extreme positions, and with the further exception that instead of a keeper of arcuate form, the balls 60, arranged in a circular row, are employed as a keeper.

While I show my lock as applied to the 50 body of a car it will be understood that I do not limit myself to this particular use of it, as it may be employed otherwise upon cars and may also be used in relations entirely independent of cars or railroading.

Having thus described my invention, I

claim as new and desire to secure by Letters Patent:

1. In a lock, the combination of a casing, a bolt mounted therein and movable relatively thereto, a slide mounted within said casing 65 and movable relatively thereto, means controllable at will for moving said slide relatively to said bolt, a member movably mounted within said casing, and a ball adapted to engage said member and also to engage said 70 slide for the purpose of enabling said slide to control the position of said member.

2. In a lock, the combination of a casing, a bolt mounted therein and adapted to travel relatively thereto, a member mounted within 75 said casing, means for moving said member relatively to said bolt, a second member movably mounted within said casing for the purpose of temporarily securing said bolt in a predetermined position relatively to said 80 casing, and mechanism controllable by the movement of said first-mentioned member relatively to said bolt for the purpose of actuating said second-mentioned member.

3. In a lock, the combination of a casing 85 provided with a slot of arcuate form, and further provided with a straight slot merging into said first-mentioned slot, a slide mounted within said straight slot, a member of arcuate form slidably mounted within said 90 slot of arcuate form, a rolling body mounted within said slot of arcuate form and adapted to engage said slide and said member for the purpose of holding said member in a predetermined position when said slide occupies a 95 predetermined position, a portion of said member engaging a portion of said slide, means for moving said slide by hand so as to move said member, and a bolt disposed within said casing and controllable by the 100 position of said member.

4. In a lock, the combination of a casing provided with an arcuate slot, a bolt slidably mounted within said casing, a plurality of balls mounted loosely within said slot and so 105 disposed as to form a row of substantially arcuate form, a slide engaging said bolt, means for actuating said slide by power for the purpose of controlling the positions of said balls, and connections from said balls to said slide 110 for the purpose of controlling the condition of said bolt.

In testimony whereof I have signed my name to this specification in the presence of two subscribing witnesses.

KINGMAN NOTT CATHER.
